Term of patent 14 years

(Cl. D44—29)

FIG. 1

FIG. 2

FIG. 1 is a plan view of a handle for kitchen tools or similar articles showing our new design.

FIG. 2 is a side elevational view thereof.

The characteristic feature of the design resides in the particular form and arrangement of the ornamental units shown in full lines, the handle being of conventional length and thickness.

We claim:

The ornamental design for a handle for kitchen tools or similar articles, as shown and described.
